UNITED STATES PATENT OFFICE.

EDMUND MORRIS, OF GRAND RAPIDS, MICHIGAN, ASSIGNOR TO WILMARSH SHOW CASE CO., OF GRAND RAPIDS, MICHIGAN.

SECTIONAL FURNITURE.

Application filed December 3, 1921. Serial No. 519,624.

To all whom it may concern:

Be it known that I, EDMUND MORRIS, citizen of the United States, residing at Grand Rapids, county of Kent, State of Michigan, have invented certain new and useful Improvements in Sectional Furniture, of which the following is a specification.

This invention relates to improvements in sectional furniture.

10 The objects of the invention are:

First, to provide an improved pilaster coupling means for sections of furniture.

Second, to provide an improved compact shelving constructure for such sectional furniture.

15 Third, to provide in such an improved sectional shelving structure an improved adjustable shelf support.

Further objects, and objects relating to 20 details and economies of construction and operation will definitely appear from the detailed description to follow.

The objects of the invention are accomplished by the devices and means described 25 in the following specification. The invention is clearly defined and pointed out in the claims.

A structure which is a preferred embodiment of the invention is fully illustrated in 30 the accompanying drawing, forming a part of this application, in which:

Fig. I is a detail perspective view of a pair of sections of furniture embodying the features of said invention, the end panel 35 being omitted.

Fig. II is a detail view of the end panel detached.

Fig. III is a detail perspective view of a separate shelf section, the pilasters being 40 omitted, but the pilaster attaching means being present.

Fig. IV is an enlarged detail of one of the pilaster couplings to the section couplings in exploded relation, showing details of such 45 structure.

Fig. V is a detail sectional view on a line corresponding to line 5—5 of Fig. IV, showing the coupling for the ends of the sectional furniture and the pilaster in place.

50 Fig. VI is an enlarged detail vertical sectional view taken on line corresponding to line 6—6 of Figs. III and VII, showing the shelf, the corner posts and the detail of the adjustable shelf support.

55 Fig. VII is an enlarged detail sectional

view through the shelf and adjustable support taken on a line corresponding to line 7—7 of Figs. III and VI.

Fig. VIII is a detail perspective view of the adjustable shelf support showing the 60 engaging member and the screw holes for securing it to the corner posts.

Fig. IX is an enlarged detail sectional view looking down at the line 9—9 of Fig. 65 VI.

Fig. X is a detail plan view of the end of one of the shelves 16, showing the projecting portions 17 between the posts.

In the drawing similar numerals of reference refer to similar parts throughout the 70 several views and the sectional views are taken looking in the direction of the little arrows at the ends of the section lines.

The various parts of the drawing will be considered by the letters and numerals of 75 reference.

A is a shelf section, B is a drawer or show case section, C is an end panel adapted to fit and cover either the end of a shelf section or of a drawer or show case section to 80 finish the same. The sections are made up of bases 1, tops 2 provided with front corner posts 3 and rear corner posts 4. The show case section may be made up of horizontal sections, the corners being divided 85 and provided with the fastening means to be hereafter described for coupling the ends of the sections together and covering the couplings with a pilaster. As these posts are substantially the same for either the 90 shelf sections or the show case sections they will not be separately described.

The corner posts in the improved structure are not spaced apart but are abutted 95 directly together. The posts 3 are notched at intervals 5 on their front to receive the end coupling means which comprise plates 6, 6 countersunk into the outer faces of said posts and provided with narrow keyhole slots 7 cut in from the front thereof with 100 depressions 8 formed in the metal around, particularly the inner ends of said slots.

Cross bolt 9 with screw head 10 and head 11 are disposed within the recesses 5 and as the heads 10 and 11 engage the plate and the bolt 9 is hexagonal it is turned up and draws the parts securely together in a very compact manner. There is clearance in the notch 5 above and below the hexagonal bolt 110 9. The edges of the post 3 are covered by

a pilaster 12 which carries the spring clip member 13 with flaring inner ends 14, 14 and engaging portions 15 adapted to snap upon and engage the hexagonal bolt 9, which 5 thereby secures the pilaster 12 detachably in position.

In the shelf sections the shelves 16 are formed with projecting end portions 17 which extend between the corner posts 3 10 and 4 and make the space continuous. The posts 3 and 4 are notched at 18 and 19 respectively. The adjustable shelf supports 20 which are made of angle bar and provided with engaging lug portions 21 have 15 projecting ends 22 which engage within the said slots 18 and 19.

The lugs 21 are cut from sections of angle bar and are spot-welded at 23 to the shelf support 20. Where the shelf is to carry 20 heavy loads the shelf support 20 is perforated at 24 to receive supporting screws which are inserted therethrough into the said corner posts. These are provided as a 25 matter of extra security and of course interfere somewhat with the ready adjustability of the shelf supports.

From this description it will be seen that I provide a shelf section with a maximum 30 of shelf room, the only portion thereof being occupied being that of the cross section of the necessary supporting corner posts. No space is wasted between the sections which are abutted closely together and protected by a very narrow pilaster.

35 These matters are of the highest consequence in securing the maximum shelf room and the maximum storage space in sectional furniture of this type.

Having thus described the invention what 40 is claimed as new and desired to secure by Letters Patent, is:

1. In sectional furniture, the combination of corner posts having notches at their fronts, side plates disposed at the inner sides 45 of said notches and countersunk thereinto with horizontal slots with the metal countersunk therearound, a cross bolt centrally disposed in said slots with heads one of which is a screw, adapted to engage the slots 50 within the said notches and retain the sections together, and a pilaster with engaging spring fingers adapted to engage the said cross bolt within the said notches, as specified.

55 2. In sectional furniture, the combination of corner posts having notches at their fronts, side plates disposed at the inner sides of said notches with horizontal slots, a cross bolt centrally disposed in said slots with

heads one of which is a screw, adapted to engage the slots and retain the sections together, and a pilaster with engaging spring fingers adapted to engage the said cross bolt within the said notches, as specified. 60

3. In sectional furniture, the combination 65 of corner posts having notches at their fronts, side plates disposed at the inner sides of said notches with horizontal slots, a cross bolt centrally disposed in said slots with heads one of which is a screw, adapted to engage the slots and retain the sections together, and a pilaster with means adapted to engage the said cross bolt within the said notches, as specified. 70

4. In a section of furniture, the combination 75 of corner posts having notches at their fronts, coupling means disposed in the said notches for coupling the posts and thereby securing the sections together, and a pilaster with means adapted to engage the coupling 80 means within said notches, as specified.

5. In a sectional furniture structure, a shelf section comprising corner posts suitably notched on their inner edges to receive 85 adjustable shelf supports, shelves with projecting ends extending between said posts, adjustable supports of angle-bar with angular lugs secured thereto with projecting ends to engage the notches in said posts, the said supports being secured to said posts by 90 screws, as specified.

6. In a sectional furniture structure, a shelf section comprising corner posts suitably notched on their inner edges to receive 95 adjustable shelf supports, shelves, adjustable supports of angle-bar with angular lugs secured thereto with projecting ends to engage the notches in said posts, the said supports being secured to said posts by screws, as specified. 100

7. In a sectional furniture structure, a shelf section comprising corner posts suitably notched on their inner edges to receive 105 adjustable shelf supports, shelves, adjustable supports with angular lugs secured thereto with projecting ends to engage the notches in said posts, the said supports being secured to said posts by screws, as specified.

8. In a sectional furniture structure, a shelf section comprising corner posts suitably notched on their inner edges to receive 110 adjustable shelf supports, shelves, adjustable supports with angular lugs secured thereto with projecting ends to engage the notches in said posts, as specified.

In witness whereof, I have hereunto set my hand and seal.

EDMUND MORRIS. [L.S.]
